UNITED STATES PATENT OFFICE.

GEORGE A. PROCTOR, OF WATERTOWN, MASSACHUSETTS, ASSIGNOR TO LOVELL-
MCCONNELL MANUFACTURING COMPANY, A CORPORATION OF DELAWARE.

MECHANICAL HORN.

1,293,919.

Specification of Letters Patent. Patented Feb. 11, 1919.

Original application filed December 10, 1913, Serial No. 805,681. Divided and this application filed January 8, 1916. Serial No. 70,586.

To all whom it may concern:

Be it known that I, GEORGE A. PROCTOR, a citizen of the United States, and resident of Watertown, in the county of Middlesex and 5 State of Massachusetts, have invented certain new and useful Improvements in Mechanical Horns, of which the following is a specification.

This invention relates to certain improvements in mechanical horns and more particularly to that type in which a diaphragm is caused to vibrate and produce the desired signal or sound by means of actuating mechanism including a vertically reciprocating 15 plunger constituting or carrying a rack bar.

This application is a division of my prior application, Serial No. 805,681, filed December 10th, 1913 (Patent No. 1,232,603, issued July 10, 1917).

20 The main object of my present invention is to simplify the construction, reduce the number of parts and reduce the cost of manufacture.

In my improved construction, I employ a 25 vertically movable rack bar and means actuated thereby for vibrating the diaphragm, and as important features of my invention, I eliminate the train of multiplying gears and compensate at least in part for this omission by increasing the length of the rack bar and so mounting it that, when depressed, it will extend a considerable distance 30 through the lower wall of the rear diaphragm casing which incloses the diaphragm 35 vibrating parts.

In my improved construction, I so design 40 and arrange the diaphragm actuating parts that it is possible for me to bring the plunger or rack bar a considerable distance forward from the rear end of the diaphragm case and thus more nearly to the center of mass of the horn. This permits the ordinary 45 form of bracket to better resist the pressure applied to the plunger in operating the horn and permits of a more suitable and effective mounting of the horn on a vehicle.

As a further important feature of my 50 construction, I employ only a single pivotal support for the diaphragm actuating parts and secure the desired movement of the diaphragm actuating member by a single member in operative engagement with the rack bar and operatively connected to the diaphragm actuating member. Thus, I directly

transmit motion from the rack bar actuated 55 member to the diaphragm actuating member and avoid the necessity of employing intermediate gearing or other motion changing parts.

In the accompanying drawing, I have 60 illustrated two simple embodiments of my invention, but I do not desire to be limited to either of these specific constructions as various changes may be made within the scope 65 of my invention as defined in the appended claims. In these drawings, to which reference is to be had and in which similar reference characters indicate corresponding parts in the several views,

Figure 1 is a central longitudinal section 70 through one form of horn constructed in accordance with my invention, and

Fig. 2 is a similar view of a second horn.

In the specific form illustrated in Fig. 1, my improved horn includes a diaphragm 10, 75 the peripheral portion of which is clamped between two diaphragm casing members 11 and 12. The front casing member 11 has its body portion spaced from the diaphragm and has a central aperture from which any 80 suitable form of resonator 13 may extend. The rear diaphragm case 12 is substantially cup-shaped with its peripheral wall 55 provided with an outwardly extending flange 85 constituting one of the two diaphragm clamps.

For agitating or vibrating the diaphragm, I provide a plunger or rack bar 52 having a series of teeth or projections 51 extending along one side or edge thereof. The rack bar 90 extends through the peripheral wall not only at the top but also at the bottom and is disposed intermediate of the diaphragm and the rear wall of the diaphragm casing 12. As shown, it is a considerable distance 95 forward from the rear edge and comparatively close to the diaphragm so that in applying pressure to the plunger to depress the latter, the strain will come more nearly to the center of mass of the horn than is possible in prior 100 constructions in which the rack bar is closely adjacent to the rear wall of the casing.

Various different means may be provided for effecting the vibration of the diaphragm upon the longitudinal movement of the 105 plunger or rack bar. Merely as one example of such a motion transmitting mechanism, I have shown a lever 56 pivoted to the rear

wall of the casing 12 and projecting directly toward the center of the diaphragm 10. A link 46, preferably in the form of a piece of wire substantially taut, connects the lever 5 to the diaphragm and is of such length as to normally hold the lever in the position illustrated. The teeth or projections 51 of the bar 52 engage with the pointed end of the lever 56 so that the latter will swing downwardly or upwardly as the bar is moved in one direction or the other. Any swinging of the lever from the position shown will effect a pull on the link 46 and a corresponding displacement of the center portion of the diaphragm. As the point of the lever passes a tooth or projection, it will snap into engagement with the next tooth or projection by reason of the elasticity of the diaphragm. With the teeth symmetrical, the same sound is produced upon the movement of the bar in one direction as in the other and this movement may be effected with great rapidity.

The operator may grasp the handle 54 at the upper end of the bar and positively move it up and down or he may merely force it down rapidly, and a suitable spring, such for instance as that shown in Fig. 2, may be employed for returning the rack bar to a normal raised position. The movement 30 of the bar may be kept within certain predetermined limits as for instance by the engagement of the handle with the upper side of the case and by the engagement of a suitable stop 14 on the lower end of the rack bar with the lower side of the case. By 35 making the rack bar of a length materially greater than the diameter of the diaphragm and by permitting it to project through the lower peripheral wall, a comparatively large 40 number of teeth and a correspondingly large number of diaphragm displacing actions are secured for each full endwise movement of the rack bar.

In Fig. 2, I have shown a second embodiment of my invention. The horn here illustrated differs in the details of construction of the diaphragm casing and resonator, but these differences are of no importance so far as my broad invention is concerned. The rack bar 85 is here shown very much closer to the rear wall of the rear diaphragm case 12^a and thus does not embody certain of the advantages hereinbefore referred to. It does embody a simple form 55 of motion transmitting mechanism and, in common with the form shown in Fig. 1, has such motion transmitting mechanism formed of two parts, one for engagement with the teeth of the rack bar and the other for engagement with the central portion of the diaphragm, the two parts moving together during an operative endwise thrust of the plunger.

In the specific construction, the power 60 transmitting mechanism is mounted upon a

transversely extending shaft or pivot 80 mounted substantially parallel to the diaphragm. A diaphragm actuator 81 is mounted to move about this shaft or pivot as a center and engage with the center of the diaphragm to vibrate the latter either by taps or by positively displacing thrusts. The member 81 is connected to a second member 87 also mounted to swing about the shaft or pivot 80 as a center. This member 75 87 has two teeth or projections 82 and 83, both of which engage with the teeth 84 of the longitudinally movable bar 85. This bar is similar in construction to that shown in Fig. 1 and may be positively moved upwardly and downwardly, or may be forced downwardly by hand and automatically returned by a spring 86. The teeth 82 and 83 bear such relationship to the teeth 84 and the pivot 80 is so designed in respect 85 to the bar that as the tooth 82 is forced down between two successive teeth on the bar, the tooth 83 will be forced into the space between two other teeth on the bar. As the bar continues to move, the tooth 83 will be 90 immediately forced out from between these teeth while the tooth 82 enters the notch or recess next adjacent to the one which it has just previously left. Thus, as each tooth on the bar 85 passes a given point, the member 81 will be positively forced first in one direction and then in the other through a limited predetermined distance and will effect a corresponding vibration or agitation 95 of the diaphragm.

Having thus described my invention, what I claim as new and desire to secure by Letters Patent is:

1. In a signal horn, the combination of a cup-shaped casing having an outwardly extending peripheral flange at the front end thereof, a diaphragm clamped to said flange and closing the front end of said casing, a rack bar vertically movable in a plane substantially parallel to the diaphragm and extending through the upper and lower walls of the casing at points spaced a considerable distance in advance of the rear end of the casing, and a diaphragm actuator extending past said rack bar and approximately the entire distance from the rear of said casing to said diaphragm and including one part engaging with the teeth of said rack bar and a second part connected thereto and movable therewith and having engagement with the central portion of the diaphragm.

2. In a signal horn, the combination of a cup-shaped casing, a diaphragm closing the front end of said casing, a rack bar vertically movable in a plane substantially parallel to the diaphragm and guided in the upper and lower walls of the casing, and means for vibrating the diaphragm upon an endwise movement of said bar, said means

including a bar actuated member engaging with the teeth of said rack bar, a diaphragm actuating member connected to said bar actuated member and movable therewith and having engagement with the central portion of the diaphragm, and a single pivotal supporting member.

3. In a signal horn, the combination of a casing, a diaphragm clamped to said casing and closing the front end thereof, a rack bar vertically movable in a plane substantially parallel to the diaphragm and extending through the upper wall of the casing, and a diaphragm actuator including one part engaging with the teeth of said rack bar and a second part connected to the first part and movable therewith and having engagement with the central portion of the diaphragm.

4. An automobile horn, including a casing, a diaphragm clamped to said casing and closing the front end thereof, a rack bar vertically movable in a plane substantially parallel to the diaphragm, and a jointed connection between the central portion of said diaphragm and the rear wall of said casing and having a part engaging with said rack bar whereby the effective length of said connection is varied and the diaphragm caused to move during the reciprocation of said rack bar.

Signed at Watertown, in the county of Middlesex and State of Massachusetts this 23rd day of December A. D. 1915.
